(57) **CLAIM**

The ornamental design for a cable connector, as shown and described.

DESCRIPTION

FIG. 1 is a perspective view of a cable connector showing the new design;

FIG. 2 is a front view of a cable connector showing the new design;

FIG. 3 is a rear view of a cable connector showing the new design;

FIG. 4 is a left side elevational view of a cable connector showing the new design;

FIG. 5 is a right side elevational view of a cable connector showing the new design;

FIG. 6 is a top view of a cable connector showing the new design;

FIG. 7 is a bottom view of a cable connector showing the new design; and,

FIG. 8 is another perspective view of a cable connector showing the new design.

The broken lines in the drawing depict environmental subject matter only and form no part of the claimed design.

1 Claim, 8 Drawing Sheets

UNITED STATES PATENT AND TRADEMARK OFFICE
CERTIFICATE OF CORRECTION

PATENT NO. : D859,317 S
APPLICATION NO. : 29/657396
DATED : September 10, 2019
INVENTOR(S) : Mu-Jung Huang, Ying-Chung Chen and Chia-Fa Chang

Page 1 of 1

It is certified that error appears in the above-identified patent and that said Letters Patent is hereby corrected as shown below:

On the Title Page

Item (72) Inventors should read:

Mu-Jung Huang, New Taipei City (TW);
Ying-Chung Chen, New Taipei City (TW);
Chia-Fa Chang, New Taipei City (TW)

Signed and Sealed this
Twenty-ninth Day of November, 2022
Katherine Kelly Vidal
Director of the United States Patent and Trademark Office
